CLAIM

The ornamental design for an acoustic device as shown and described.

DESCRIPTION

FIG. 1 is a front perspective view of an acoustic device showing our new design in a horizontal position;

FIG. 2 is a top view thereof;

FIG. 3 is a bottom view thereof;

FIG. 4 is a front view thereof;

FIG. 5 is a rear view thereof;

FIG. 6 is a left side view thereof;

FIG. 7 is a right side view thereof;

FIG. 8 is a front perspective view of an alternative embodiment of the acoustic device in the horizontal position;

FIG. 9 is a front perspective view of an alternative embodiment of the acoustic device in the horizontal position;

FIG. 10 is a front perspective view of an alternative embodiment of the acoustic device in the horizontal position with symbolic break lines;

FIG. 11 is a front perspective view of an alternative embodiment of the acoustic device in a vertical position;

FIG. 12 is a top view thereof;

FIG. 13 is a bottom view thereof;

FIG. 14 is a front view thereof;

FIG. 15 is a rear view thereof;

FIG. 16 is a right side view thereof;

FIG. 17 is a left side view thereof;

FIG. 18 is a rear perspective view of an alternative embodiment of the acoustic device of FIG. 11 in a vertical position;

FIG. 19 is a rear perspective view of an alternative embodiment of the acoustic device in the vertical position;

FIG. 20 is a rear perspective view of an alternative embodiment of the acoustic device in the vertical position; and,

FIG. 21 is a rear perspective view of an alternative embodiment of the acoustic device in the vertical position with symbolic break lines.

The drawings contain symbolic break lines in FIGS. 10 and 14. Any portion between the break lines forms no part of the claimed design.

(Continued)

In the drawings, the broken lines depict environmental structure and form no part of the claimed design.
